Patented Nov. 12, 1912.

UNITED STATES PATENT OFFICE.

ALBERT MCKINNEY AND NEWTON RICHARDSON, OF TORONTO, ONTARIO, CANADA.

FILING DEVICE.

1,043,952.

Specification of Letters Patent. Patented Nov. 12, 1912.

Application filed February 7, 1912. Serial No. 676,107.

To all whom it may concern:

Be it known that we, ALBERT MCKINNEY and NEWTON RICHARDSON, both subjects of the King of Great Britain, and residents of the city of Toronto, county of York, Province of Ontario, in the Dominion of Canada, have invented certain new and useful Improvements in Filing Devices, of which the following is a specification.

- 10 The invention relates to improvements in filing devices, as described in the following specification and illustrated in the accompanying drawings that form part of the same.
- 15 The invention consists essentially in the novel construction and arrangement of parts, whereby the sheets filed are suspended upon a telescopic member having the outer movable portion supported from a
- 20 slideable frame.

The objects of the invention are, to facilitate the filing and removal of large sheets such as garment patterns, and to devise a filing device which will allow the quick selection and removal of any pattern desired without the necessity of handling the others on the file, thereby effecting a considerable saving of time and also obviating the mutilation of the patterns.

- 25 In the drawings, Figure 1 is a perspective view of the improved filing device shown in its closed position and showing a number of sheets filed thereon representing patterns or other sheets. Fig. 2 is a perspective view showing the device distended and illustrating the method of removing the desired sheet. Fig. 3 is a perspective detail of a slightly modified form of the supporting frame construction. Fig.
- 30 4 is a small perspective view of a modified form.

Like numerals of reference indicate corresponding parts in each figure.

Referring to the drawings, 1 is the rigid portion of the device in the form of a bracket adapted to be rigidly secured to a wall or other vertical support and having the right angular extension 2 projecting forwardly from the upper end said extension having a central longitudinal slot 3 therein.

4 is a tubular member rigidly secured in the lower end of the bracket member 1 and arranged parallel to the extension 2, said tubular member forming the rigid end of the filing bar.

5 is a right angular shaped frame having the upper member 6 thereof adapted to rest upon the top of the extension 2 and to slide thereon, said member 6 being slidably secured to the extension 2 by a pair of rivets or bolts 7 extending downwardly through the slot 3.

8 is a bar rigidly secured to the lower end of the perpendicular portion of the frame 5 and extending inwardly parallel with the top portion and having a reduced end 9 adapted to telescope into the tube 4.

The bracket member 1 may be formed in almost any desired shape so long as it is provided with a forwardly projecting portion at the top to carry the outer frame.

A slightly modified form of connecting the sliding frame to the rigid member is shown in Fig. 3, the extension end 2 having the laterally extending lugs 10 formed at the outer end bent upwardly and inwardly and forming a guide for the upper member 6 of the sliding frame, said upper member having correspondingly arranged lugs 11 bent downwardly and inwardly and loosely embracing the extension 2.

In the use of this device, the outer vertical portion of the frame 5 forms a handle for sliding the said frame outwardly. When the frame 5 is drawn to the limit of its outward movement the inner end of the bar 8 is withdrawn just clear of the outer end of the tube 4 thus leaving a narrow slit opening 12 sufficiently wide to allow the ready placing and removal of one of the patterns or other sheets held on the file. The patterns are thus placed in position so that the tube 4 extends through a suitable hole punched in said pattern and when the desired number of patterns are placed on the file the movable frame 5 is pushed inwardly, the bar 8 telescoping into the tube 4 and the shoulder portion 13 thereof abutting the end of said tube. The patterns are thus supported upon the horizontal bar so as to hang free and perpendicular. When it is desired to use a pattern which is on the file, the operator draws out the frame and slides the various patterns from the tube 4 on to the bar 8 until the desired pattern is reached.

This pattern is then slipped into the narrow slit 12 and the forward patterns are moved back on to the tube and the outer end of the frame closed in.

A very simple and cheap form of file is thus produced and it will be readily under-

stood that a very considerable saving will be effected in the time of employees in large factories where numerous patterns are used as it is the custom at the present time to file 5 a number of patterns on a hook or nail and whenever a pattern is required the whole bunch has to be removed, the proper pattern extracted and the bunch replaced. It will also be apparent that the patterns will 10 be much longer lived owing to the fact that they will not be continuously handled in an effort to obtain the required one from the bunch.

Many modifications of construction of this 15 file may be made without departing from the spirit of the invention so long as the main feature of a slidable frame carrying a telescoping member adapted to telescope into a rigidly supported tube is adhered to.

20 What we claim as our invention is:—

1. In a filing device, a bracket having a rigid angular extension, a filing member rigidly secured in said bracket and arranged in parallel relation to said bracket extension, 25 and a member slidably secured to said bracket extension and carrying a member adapted to telescope with said rigid filing member and to be retained in alinement with said rigid member in the extended 30 position.

2. In a filing device, a rigid bracket adapted to be secured in a vertical position and

having a horizontal extension from the top thereof and a horizontal tubular extension from the bottom, a frame slidably supported 35 on said bracket extension, and a horizontally arranged rod rigidly secured to said slidable frame and adapted to telescope said tubular extension.

3. In a filing device, a rigid bracket member having a horizontal extension from the top formed with a longitudinal slot therein, a tubular member rigidly secured to said bracket member adjacent to the lower end and arranged parallel with said horizontal 45 extension, a frame having a horizontally arranged portion adapted to rest on the top of the extension from said bracket and having a pair of rivets secured therein and extending through said slot, and a rod rigidly 50 secured in the vertically arranged portion of said frame in horizontal alinement with said tube and having a reduced end adapted to telescope said tube and a shoulder portion adapted to abut the end of said tube 55 when the device is closed.

Signed at the city of Toronto, county of York, Ontario, Canada, this 24th day of January 1912.

ALBERT McKINNEY.
NEWTON RICHARDSON.
